UNITED STATES PATENT OFFICE.

EDGAR E. GREVE, OF BELLEVUE, PENNSYLVANIA.

SAFETY HOOK.

Application filed February 23, 1928. Serial No. 256,144.

This invention relates to safety hooks, and particularly to that class of safety hooks employed in connection with oil and gas well drilling and operating apparatus, the present invention being especially designed to be used in connection with hydraulic swivels and elevators employed.

Safety hooks of the class to which my invention relates are of necessity very heavy structures, in order to support the weight suspended therefrom in practice, and should have safe and relatively heavy, durable closure means for preventing the means carried thereby from becoming accidentally disconnected therefrom.

The prime object of my invention is to provide, in a hook of the character specified, a closure member and efficient actuating and locking means for the said closure member.

In the accompanying drawings, which illustrate an application of my invention:

Fig. 1 is a side elevational view of a hook embodying my invention;

Fig. 2, a front elevational view;

Fig. 3, a sectional view taken on the line III—III of Fig. 1, showing the closure member actuating means positioned on said member midway of its travel; and

Fig. 4, an enlarged detail sectional view of the closure member.

Referring to the drawings, and as preferred, my improved hook comprises a body portion 5 of rugged construction, a shank or neck portion 6 having a collar 7, and a bill portion 8. Said hook is designed to be supported from a cross-head 9 of a clevis 10. As illustrated, the upper end of the neck 6 is threaded, as shown at 11, to receive a cap-nut 12 mounted on anti-friction bearing 13, interposed between the nut and the cross-head, and the clevis is secured to the cross-head by trunnions 14. It will be understood that this construction will permit the hook to swivel relatively to its support; however, means are provided to prevent the swiveling action when desired. These means comprise a boss 15 preferably welded to the neck portion of the hook adjacent to the collar 7, a spring pressed pin 16, and a recess 17 formed in the cross-head.

The mouth or the opening of the hook is adapted to be controlled by a latch or closure member, and this member, together with the combined actuating and locking means for the closure member, constitute important and characteristic features of the present inven-

tion. The closure member, designated generally by the numeral 18, is preferably of the form particularly shown by the detail view of Fig. 4, and is designed to be pivotally mounted on a pivot pin 19 carried in a boss 20 formed on or welded to the neck of the hook.

Member 18 is cored out or cut away, as shown at 21, and is provided with an opening 22 in its front face to enable it to be pivotally mounted on the boss 20 and to overlap the hook or its neck portion when moved to open position, as shown by dotted lines in Fig. 1. The front face of the closure member, for a portion of its length, is flat, as shown at 23, and for a portion of its length is arched or curved, as shown at 24, and adjacent the ends of the arched portion, upper and lower recesses or notches 25 and 26 are provided. The lower end of the closure member is cut away at 27 to snugly fit the bill portion of the hook when in closed position.

The closure member actuating and locking means comprises a pivotally mounted yoke-like structure 28 designed to be mounted on a pivot pin 29 carried in lugs or a boss 30 welded or otherwise secured to the neck portion 6 of the hook. As illustrated and as preferred, the said actuating and locking means includes yoke castings or members 31, a yoke or U-member 32 having a roller contact 33 arranged on the front face of the closure member, and means for yieldingly mounting member 32 on members 31. Said yielding means include a spring 34 positioned in each of the tubular chambers 35 of the casting 31, a bushing or follower 36, and adjusting nuts 37 carried on the threaded ends of member 32.

By means of the construction just described, it will be understood when the closure member and its combined actuating and locking means are in the full line position, Fig. 1, the closure member is securely maintained in closing position by the said actuating means, and that to effect an opening movement of member 18, yoke structure 28 is swung downwardly from full line position to dotted line position. During the downward movement, contact roller 33 is moved out of the notch 25, over the curved portion 24 of closure member 18, and into the notch 26.

To again close the hook opening, the yoke is swung upwardly, causing the travel of the

contacting roller in an opposite direction over the front face of member 18. It will be noted that member 18 may be moved from closing to open position, and vice versa, only 5 by the movement of the actuating means, and when so moved it is locked in either position by the said means. It will also be noted that both the closure member and its actuating means are pivotally supported 10 and are adapted to oscillate in unison on their respective pivots, and, further, that the highest point of the arc or curved portion of the face of the closure member is on the center line of the pin on which it pivots.

15 I claim:

1. In a safety hook, a pivotally mounted closure-member and pivotally mounted closure-member actuating and locking means movable substantially longitudinally on the closure-member to move said member from open to closed position and lock the member in closed position.
2. In a safety hook, a pivotally mounted closure-member, and pivotally mounted closure-member actuating and locking means movable substantially longitudinally on the closure-member to move said member from closed to open position and lock the member in open position.
3. In a safety hook, a pivotally mounted closure-member, and pivotally mounted closure-member actuating and locking means movable on the closure-member to move said member from open to closed position and lock the member in closed position, said actuating and locking means including a resiliently mounted member bearing upon and arranged to travel substantially longitudinally on the closure-member for effecting a movement thereof.
4. In a safety hook, a pivotally mounted

closure-member having a face thereof provided with a curved bearing portion and depressions adjacent the curved bearing, and one on each side of the axis of the closure member and actuating and locking means movable substantially longitudinally on the face of the closure-member and over said curved bearing from one side of the axis of said closure member to the other side to effect 45 a movement of said member, and into the depressions thereof to lock the closure-member.

5. In a safety hook, a closure member therefor pivotally mounted intermediate its 55 ends, and expansible and contractile actuating and locking means for said member, said means being pivoted for movement substantially longitudinally of said member and across the axis of said member and for engagement with the member on opposite sides of said axis.

6. In a safety hook, a closure member therefor pivotally mounted intermediate its 65 ends, and an expansible and contractile actuating and locking means for said member, said means being carried by the hook and mounted for movement at a portion thereof in contact with and substantially longitudinally of said member and across the axis of 70 said member for engagement with the member on both sides of said axis.

7. In a safety hook, a closure member therefor, an expansible and contractile means, said means being movable substantially longitudinally of the closure member and engageable with the member at 75 spaced locations and in each location adapted to urge the same and lock it in a different position.

In testimony whereof I affix my signature.
EDGAR E. GREVE.
